(57) **CLAIM**

The ornamental design for a face shield, as shown and described.

DESCRIPTION

FIG. 1 is a perspective view of a face shield showing my new design;

FIG. 2 is a top plane view thereof;

FIG. 3 is bottom plane view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is another perspective view of the face shield of FIG. 1 shown as being worn by a user; and,

FIG. 9 is another perspective view of the face shield of FIG. 1 shown in a flat unfolded configuration.

In the Figures, the broken lines are for the purpose of illustrating environment and form no part of the claimed design.

1 Claim, 9 Drawing Sheets
